UNITED STATES PATENT OFFICE.

RUBY E. MITZEL, OF LARAMIE, WYOMING.

SPARK-ARRESTER.

1,263,457.

Specification of Letters Patent. Patented Apr. 23, 1918.

Application filed October 16, 1917. Serial No. 196,933.

To all whom it may concern:

Be it known that I, RUBY E. MITZEL, a citizen of the United States, residing at Laramie, in the county of Albany, State of

Wyoming, have invented certain new and useful Improvements in Spark-Arresters; and I do hereby declare the following to be a full, clear, and exact description of the invention, such as will enable others skilled 10 in the art to which it appertains to make and use the same.

This invention relates to spark arresters. The object of the invention is to provide an improved form of spark arrester for locomotives, which will effectively prevent the emission of ignited cinders and burning embers from the smoke stack to cause forest fires, prairie fires or other destructive burnings.

20 It is a further object of the invention to construct a spark arrester so that it will permit the maintenance of a proper draft to the locomotive fire box and smoke box.

With the above objects in view, and such 25 others relating to the details of construction, as may hereinafter appear, my invention will now be fully set forth and described, reference being had to the accompanying drawings.

30 In the drawings:

Figure 1 is an elevation of the arrester mounted within a smoke box,

Fig. 2 is a vertical section on the line 2-2 of Fig. 3,

35 Fig. 3 is a section on line 3-3 of Fig. 2, Fig. 4 is a section on line 4-4 of Fig. 2, Fig. 5 is a section on line 5-5 of Fig. 2.

Referring more particularly to the drawings, 1 represents the forward flue sheet of 40 usual construction into which the flues 2 are connected. The smoke box 3 which lies in front of the flue sheet 1 has rising therein the exhaust nozzle 4, said exhaust nozzle 4 having its upper end projected through the 45 dead plate 5 in the usual manner.

The dead plate 5 extends horizontally forward from an upwardly and rearwardly inclined baffle plate 6 whose upper end extends rearwardly in, or is secured to a horizontal 50 section 7, the rear edge of the latter abutting the flue sheet 1. Mounted below the forward edge of the dead plate 5 is a baffle plate 8 to which is secured an adjustable sheet 9 by pin and slot connections so that 55 the sheet 9 may be extended downwardly and forwardly in continuation of the incline

of the plate 8, to provide a proper regulation of the circulation of the products of combustion.

Mounted upon the dead plate 5 is the 60 spark arrester structure consisting essentially of a lower section 10 and an upper section 11 which taper in opposite directions from the flanged joint 12 by means of which the sections are bound together. The sections 10 and 11 are constructed from sheet metal of suitable weight, and the several sheet metal plates are outwardly flanged and bolted or riveted together or are connected together by angle-iron bars riveted 65 according to the method which is found to be most suitable. The lower section 10, in the embodiment shown, consists of four generally quadrangular plates joined along their vertical edges and at their lower ends being suspended between and spaced from quadrangularly arranged sets of outer plates 13 and inner plates 14, the plate 10 being equi-distantly spaced between the plates 13 and 14 upon stay bolts 15. The plates 13 70 are comparatively long low elements having their lower edges outwardly flanged to rest upon the dead plate 5, and having their ends outwardly flanged to be joined one to the other around the structure 10. The side 75 plates, aside from being spaced from the plates 13 and 14, also have their lower ends spaced or riveted above the dead plate 5, so that products of combustion passing downwardly between the plates 13 and 10, 80 may then turn upwardly and enter the spark arrester through the spaces between the plates 10 and 14. Projecting inwardly from the walls of the section 10, near the upper end of the latter, is a plurality of 85 rows of horizontally extending pins or spurs 16, the pins of one row being staggered with respect to the pins of another row, so that each one serves to interrupt the passage upwardly of the sparks and cinders 90 which are drawn along with the products of combustion.

The upper section 11 is formed of a set of quadrangular plates similar to those forming the sides of the section 10, and at their 105 upper ends have secured thereto in inwardly spaced relation a flue structure 17, the latter being supported by means of a plurality of rows of stay bolts 18 which extend completely around the structure 11, these bolts 110 being also arranged in vertical staggered relation. The space between the flue 17 and

the walls of the structure 11 provides passages through which the products of combustion are induced to flow downwardly into the spark arrester structure, and then upwardly through the flue, the stay bolts 18 serving to arrest and throw down the cinders and embers which are being carried along by the products of combustion. The upper end of the flue 17 is preferably projected slightly above the side plates of the section 11, and supports thereon the lower smoke stack section 19.

The products of combustion which are released into the smoke box 3 are drawn by the exhaust blast from the nozzle 4 through the passages formed by the plates 10, 13 and 14 and the plates 11, together with the flue 17 into the spark arrester structure, and by reason of the tortuous paths through which they must pass, and because of the pins 16 and stay bolts 15 and 18 around which they flow, the burning cinders and embers are induced to fall before passing out of the smoke funnel. The structure, aside from causing the cleansing of the products of combustion of cinders and sparks, provides an effective regulation of the draft. The downward direction which is given to the several divisions into which the products of combustion are divided is particularly effective in removing the cinders from the products.

What I claim as my invention is:

1. A spark arrester, comprising in combination with the smoke box and smoke stack of a locomotive, a dead plate extending horizontally across the smoke box and adapted to have the exhaust nozzle extended therethrough, a spark arrester structure

mounted upon the dead plate and consisting of upper and lower oppositely tapered sections, inner and outer plates supporting the lower section above the dead plate and also in spaced relation to the latter, and to said supporting plates, a flue structure mounted within the upper section at the upper end thereof and also in spaced relation to the walls of said upper section, and a stack section connecting the flue structure to the smoke stack.

2. A spark arrester, comprising in combination with the smoke box and smoke stack of a locomotive, a dead plate extending horizontally across the smoke box and adapted to have the exhaust nozzle extended therethrough, a spark arrester structure mounted upon the dead plate and consisting of upper and lower oppositely tapered sections, inner and outer plates supporting the lower section above the dead plate and also in spaced relation to the latter, a flue structure mounted within the upper section at the upper end thereof and also in spaced relation to the section, a stack section connecting the flue structure to the smoke stack, and a plurality of series of pins projecting across the passages between said inner and outer plates and the lower section and inwardly from the walls of the sections to interrupt the passage of the products of combustion through the arrester structure.

In testimony whereof, I affix my signature in the presence of two witnesses:

RUBY E. MITZEL.
